UNITED STATES PATENT OFFICE.

JULES A. PERRAULT AND WILLIAM ALVAN HITCHCOCK, OF BOSTON, MASSACHUSETTS.

DESIGN FOR A COMBINED PHONOGRAPH AND MOVING-PICTURE CABINET.

Application filed August 14, 1922. Serial No. 3,370. Term of patent 7 years.

To all whom it may concern:

Be it known that we, JULES A. PERRAULT and WILLIAM ALVAN HITCHCOCK, citizens of the United States, and residents of the city of Boston, in the county of Suffolk and Commonwealth of Massachusetts, have invented a new, original, and ornamental Design for Combined Phonograph and Moving-Picture Cabinet, of which the following is a specification, reference being had to the accompanying drawing, forming a part thereof.

The figure is a perspective view of a combined phonograph and moving picture cabinet, showing our new design.

We claim:

The ornamental design for a combined phonograph and moving picture cabinet, as shown.

JULES A. PERRAULT.
W. ALVAN HITCHCOCK.
